UNITED STATES PATENT OFFICE

CRESTON W. SCOTT, OF SPRINGFIELD, MASSACHUSETTS, ASSIGNOR TO THE FIBEROID CORPORATION, OF INDIAN ORCHARD, MASSACHUSETTS, A CORPORATION OF MASSACHUSETTS

METHOD OF FORMING INLAYS

Application filed April 12, 1929. Serial No. 354,668.

This invention relates to the production of inlaid articles of pyroxylin plastic materials such as celluloid, fiberloid, etc., and has particular reference to the manufacture of monogrammed or otherwise ornamented striking faces for wooden golf clubs. One object of the invention is to produce inlaid designs of any desired degree of complexity without the necessity of fine hand-work and by methods permitting of mass production. Monograms, of course, will not ordinarily be produced in mass unless used for trade-mark purposes; but the invention is in another aspect directed to the production of this species of design with a degree of accuracy not hitherto attainable. A further object of the invention is the production of inlaid designs of a degree of permanence permitting their use in the striking face of a golf club.

Referring to the drawings:

Fig. 1 is a plan view of a blank in which the inlay is to be set;

Fig. 2 is a similar view showing the engraving of a recess to receive the inlay;

Fig. 3 is a section on line 3—3 of Fig. 2;

Fig. 4 is a plan view of a mold in which the inlay is formed;

Fig. 5 is a section on line 5—5 of Fig. 4;

Fig. 6 is a face view of the molded insert;

Fig. 7 is a section on line 7—7 of Fig. 6;

Fig. 8 is a plan view of the blank and mold insert after assembly;

Fig. 9 is a section on line 9—9 of Fig. 8;

Fig. 10 is a plan view of the finished article; and

Fig. 11 is a section on line 11—11 of Fig. 10.

In the description of the inlaying process which follows, I have chosen a monogram as the design to be reproduced, for this embodies most of the difficulties present in the reproduction of any type of design for an inlay. The monogram shown has its letters interlaced, but separated letters can be formed with equal facility. The main difficulty in forming an inlay having any degree of complexity of course lies in securing perfect registry between all parts of the inlay and the recess into which the inlay is to be set. By my improved process, all parts of

the inlay are at all times positively held in perfect registry, and trouble from this source is avoided.

In the practice of my invention, I first prepare a blank 15 of pyroxylin plastic or similar composition by forming in its surface a recess corresponding to the design to be inlaid. This may be done by molding, but preferably by cutting the recess accurately to correspond with a larger size template on one of the common pantograph engraving machines. The recessed design is shown as comprising a border 16 and an interlaced monogram 17.

From the same template, and with the same reduction setting of the pantograph, is formed a recessed mold 18, preferably of brass or other metal. This mold is cut with a border 19 and a monogram 20 exactly similar in size to those cut in the blank 15 except that the recesses in the mold are preferably slightly deeper than those in the blank. The mold is also preferably formed with a blank severing edge 21 surrounding the recessed design and operating to mold the body of the inlay blank. This blank 22 is of a pyroxylin plastic or similar composition and is formed in the mold 18 in the customary manner of molding such articles. When formed, this blank will have a raised portion 23 corresponding to the border of the design and similarly raised portion 24 corresponding to the monogram. These portions are of exactly the correct shape to fit into the recesses 16, 17 of the blank, except that they are slightly longer than the recesses are deep, and are held together solidly and without chance for slippage or distortion by the main body portion of the inlay blank.

The interfitting surfaces of the main blank and the inlay blank are then coated with a suitable pyroxylin plastic cementing solvent and are pressed tightly together as shown in Figs. 8 and 9. During this assembling operation, the body of the inlay blank holds the different portions of the design firmly together so that any displacement or lack of registry between the several details is impossible. After firm adhesion has resulted from the drying of the solvent, the body portion

of the inlay blank is cut or milled off, leaving only the design imbedded in the body of the main blank as shown at 25 in Figs. 10 and 11. The inlay as thus produced is substantially integral with the main blank so that it cannot be dislodged by the impact of a golf club on the ball, and is of any depth desired to permit shaping of the surface or to provide for wear. If the inlay is for the striking face of a golf club, the inlaid blank is then mounted in its proper position on the club and finished off flush with the striking face. The rigidity and permanence of the inlay permit this to be done without danger of disturbing the main design.

What I claim is:

1. A method of making plastic inlays which comprises forming in the surface to be inlaid recesses corresponding in configuration to the design to be produced, forming an inlay blank with projecting portions shaped to interfit with the recesses and held solidly in their proper relative positions by the integral body portion of the inlay blank, said projections being of slightly greater length than the depth of the recesses, applying to the recess and to the projecting portions of the inlay blank a substance adapted to cause their adhesion, inserting the projecting portions of the inlay blank into the corresponding recesses while the projections are still held assembled by the body portion, and then cutting away the body portion of the inlay blank and that part of the projecting portions extending outside the recesses.

2. A method of making plastic inlays which comprises mechanically cutting from a template recesses in the surface to be inlaid, corresponding in configuration to the design to be produced, similarly cutting a mold from the same template, molding an inlay blank in the mold with projecting portions shaped to interfit with the recesses and held solidly in their proper relative positions by the integral body portion of the inlay blank, applying to the recess and to the projecting portions of the inlay blank a substance adapted to cause their adhesion, inserting the projecting portions of the inlay blank into the corresponding recesses while the projections are still held assembled by the body portion, and then cutting away the body portion of the inlay blank.

In testimony whereof I have affixed my signature.

CRESTON W. SCOTT.
